UNITED STATES PATENT OFFICE.

ELIAS B. BIRGE, OF ST. PAUL, MINNESOTA.

STEAM-BOILER.

SPECIFICATION forming part of Letters Patent No. 356,914, dated February 1, 1887.

Application filed October 18, 1886. Serial No. 216,568. (No model.)

To all whom it may concern:

Be it known that I, ELIAS B. BIRGE, of St. Paul, in the county of Ramsey and State of Minnesota, have invented a new and Improved Steam-Boiler, of which the following is a full, clear, and exact description.

My invention relates to upright steam-boilers designed more especially for fire-engines; and the invention consists in the construction, arrangement, and combination of parts, all as hereinafter described and claimed.

Reference is to be had to the accompanying drawings, forming a part of this specification, in which similar letters of reference indicate corresponding parts in all the views.

Figure 1 is a sectional elevation of a boiler constructed in accordance with my invention. Figs. 2 and 3 are sectional plan views taken, respectively, on the lines *x x* and *y y* of Fig. 1; and Fig. 4 is a sectional plan view on line *z z*, Fig. 1, the grate-bars being omitted.

The fire-box A, grate-bars B, and boiler-casing C, with smoke-stack C', may be of the usual or of any approved construction, and the tubes D may be set in the tube-plates E F of the boiler in the usual manner.

The fire-box A is made of less diameter than the boiler C to form the water-leg A', and within the fire-box A is or are placed the pipes G, (one or more,) arranged to take water from the water-leg A', and to discharge it above the lower tube-plate, E. In this instance the tubes G are bent, as shown in Figs. 1 and 4, to increase the heating-surface, and are all upwardly inclined and connected at their upper ends to the central large tube or chamber, H, fitted in the lower tube-plate, E, and formed with several discharge-openings, a, above the tube-plate, so that when heated 4c there will be a constant flow or circulation of water from the bottom of the water-leg A', through the pipes G and pipe H, to the main upper water-space of the boiler.

Above the upper tube-plate, F, is placed the 45 coiled pipe J, one end, *j*, of which terminates in a rose within the main water-space, as shown in Fig. 1, while the other end, *j'*, passes down through the two tube-plates to the fire-box A, and to this lower end of the pipe J is 50 connected the feed-water-supply pipe K, and also the pipe L, which is carried around the fire-box and connected with the eduction-port of the pump M.

The induction-port of the pump M is connected by the pipe N to the lower part of the

water-leg A' of the boiler, so that when the pump is operated by the lever O, or otherwise, the water in the boiler will be drawn from the lower part of the boiler, passed through the pump and pipe L in the fire-box, 60 then through the pipe J, and heated therein above the tubes D, and returned in spray or small streams to the upper part of the boiler through the rose *j*. The pump M need be operated only at the time of starting the fires to 65 circulate the cold water in the boiler to cause rapid heating, for as soon as the water is considerably heated a circulation will begin and continue through the pipes G H, so that the water will constantly pass from the leg A' 70 through the pipes G and chamber H in the fire-box, and out the discharge openings *a* to the boiler again. The feed-water entering at pipe K will pass through the pipe J, and become heated therein by the heat and products of 75 combustion rising through the tubes D before entering the boiler, and to prevent the feed-water from entering the pump M, I fit on the pipe L, near the pump, the cock P, which may be opened when the pump is to be operated by 80 a wrench or lever, P'.

By arranging the boiler accessories as described a very rapid generation of steam is effected, and the heat from the burning fuel is utilized to the best advantage.

Having thus fully described my invention, I claim as new and desire to secure by Letters Patent—

1. The pipe J, coiled above the boiler-tubes, and terminating at one end in the water-space and at the other in the fire-box, in combination with the feed-pipe K, connected to the pipe J in the fire-box, substantially as described.

2. The pump M, connected by pipe N to the water-leg A' of the boiler, and connected by pipe L in the fire-box to the pipe J, located in the smoke-box above the fire-tubes, and directly exposed to the products of combustion, and terminating in the water-space, substantially as described.

3. The lower tube-plate, E, having the pipe H, fitted in it, formed with the discharge-openings *a* and projecting in the fire-box, in combination with the pipe G, connected with the water-leg A' and with the pipe H, substantially as and for the purposes set forth.
